UNITED STATES PATENT OFFICE.

WILLIAM F. NORMAN, OF NEVADA, MISSOURI.

GRAVE-MARKER.

1,276,798.

Specification of Letters Patent. Patented Aug. 27, 1918.

Application filed August 21, 1917. Serial No. 187,455.

To all whom it may concern:

Be it known that I, WILLIAM F. NORMAN, a citizen of the United States, residing at Nevada, in the county of Vernon and State 5 of Missouri, have invented certain new and useful Improvements in Grave-Markers, of which the following is a specification, reference being had therein to the accompanying drawing.

- 10 This invention relates to improvements in grave markers, one object of the invention being the provision of a temporary marker especially adapted for use in connection with temporary graves.
- 15 A further object of this invention is the provision of a marker of this type which is provided with a supporting member carrying a name plate of novel construction, the piercing end of the supporting member being so constructed as to permit of the easy sticking of the marker in the earth and the support thereof after being placed in position.

20 A still further object of this invention is the provision of a device of this character which is simple and inexpensive in construction and readily placed in use.

In the accompanying drawings:

25 Figure 1 is a front elevation of the complete marker.

Fig. 2 is a rear elevation thereof.

Fig. 3 is a section taken on line 3-3 of Fig. 1.

30 Fig. 4 is a section taken on line 4-4 of Fig. 1.

Referring to the drawings, the numeral 5 designates the supporting member which is made from a single piece of metal and bent to provide the two parallel flanges 6 with 35 the entering point 7, said point at its extremity being bent outwardly to the opposite side of the supporting member to the flanges, while the lower edges of the flanges are beveled as at 8 to assist in the introduction of the supporting member in the earth.

40 The supporting member is further provided with the three openings 9, 10 and 11, the opening 9 constituting a means whereby an emblem or other ornament may be attached, while the other openings are adapted 45 to receive the terminals 12 of the rivets 13

which support the card carrying member 14 upon the member 5.

The card carrying member consists of a single sheet of metal bent to provide the 55 rear wall 15 having the longitudinal reinforced depressions 16 and the inturned edge 16'. The front wall 17 is bent co-extensively with the rear wall and is provided with the flange 18 which constitutes a fastening for 60 engaging one end of the rear plate of the member while the lower edge is bent outwardly to provide an opening 19 at the right hand side for the introduction of the sheet 20 which carries the data. The front wall 65 75 of this member is further depressed outwardly to provide a receptacle 21 to retain the sheet 22 of glass so that the data carrying member is protected thereby. It will thus be seen that the data carrying member 70 is protected from the weather by the peculiar formation of the supporting member in that the top is entirely closed and all other edges are positioned that the rain is drained therefrom.

The front wall is otherwise ornamental so that the device when in place, although temporary, is more ornamental than the ordinary grave indicators or markers.

What I claim as new is:

80 The herein described grave marker including a supporting member and a card carrying member, said card carrying member being made from a single sheet of material divided centrally and longitudinally and bent 85 so that the bent edge forms the top thereof, the front wall being provided with a slight opening, the rim of which is outwardly depressed to coöperate with the rear wall to provide a receptacle for a card index and a 90 transparent covering, there being formed upon one side edge of the front wall a flange for embracing the corresponding edge of the rear wall, both the front and rear wall centrally thereof and at points above and below, the opening in the front wall being apertured, and fastening devices in said apertures 95 for attaching the card carrying member to the support.

100 In testimony whereof I affix my signature.

WILLIAM F. NORMAN.
